UNITED STATES PATENT OFFICE.

BERNARD WAHL AND JACOB LAMBERTY, OF KEWANEE, ILLINOIS.

MUSIC-LEAF TURNER.

No. 921,124.

Specification of Letters Patent.

Patented May 11, 1909.

Application filed April 13, 1902. Serial No. 426,791.

To all whom it may concern:

Be it known that we, BERNARD WAHL and JACOB LAMBERTY, citizens of the United States, residing at Kewanee, in the county of Henry and State of Illinois, have invented certain new and useful Improvements in Music-Leaf Turners; and we do declare the following to be a full, clear, and exact description of the invention, such as will enable others skilled in the art to which it appertains to make and use the same.

This invention relates to music leaf turners and has for its object to provide a turner which will quickly and efficiently turn the leaves of a book of music without having to be manipulated with the hands.

Another object is to provide in a device of this kind novel means for turning the leaves of the book either forward or backward.

Another object is to provide a device of this kind which will be easily and conveniently operated and which may be cheaply manufactured, which will be simple in construction and will not get out of order.

For these and still other objects which will appear as the description proceeds the invention consists of certain novel features, arrangements and combinations of parts of which the herein described music leaf turner is one of many possible embodiments.

While herein the description refers to minute details of the invention, the invention is not limited to these as the details of construction and combination may be greatly varied without departing from the spirit and scope of the invention.

In the annexed drawing forming a part of this specification in which like reference characters refer to like parts throughout the several views and which are for illustrative purposes and therefore not drawn to any particular scale, Figure 1 is a front view of a music rack with the music turner applied; Fig. 2 is a side elevation of the same; Fig. 3 is an enlarged front elevation of the music leaf turner proper; Fig. 4 is a top view; Fig. 5 is an enlarged front view with the cover of the mechanism removed; Fig. 6 is a side view of the same; Fig. 7 is a side vertical sectional view; Fig. 8 is a vertical sectional view taken at right angles to the section of Fig. 7; Fig. 9 is a sectional view taken on the line 9—9 of Fig. 6; Fig. 10 is a sectional view taken on the line 10—10 of Fig. 3; Fig. 11 is a sectional view taken on the line 11—11 of Fig. 3; Fig. 12 is a sectional view taken on the line 12—12

of Fig. 3, and, Fig. 13 is a perspective view of the actuating rod detached.

Referring more particularly to the drawing, the herein described embodiment of my invention is shown in connection with a music rack having a tubular standard 1 provided with the usual supporting legs 2, the upper end of the standard 1 being provided with an enlarged tubular support 3 to which may be secured the music holder 4 and which supports the operating mechanism of the leaf turner.

The music holder 4 is of usual form and comprises a bottom board 5 hingedly connected at its midpoint 6 and provided with cross arms 7 pivoted as at 8 to the support 3. At a convenient distance intermediate the ends of the tubular support 3, the rear of said support is cut away to form a slot 9. Just below said slot and concentric with said tube is a bearing opening 10 adapted to rotatably and slidably receive the actuating rod 13 carrying an elongated pinion 15 and a series of rack teeth 16, the part 15 being wholly exposed by said slot and the part 16 being partly exposed thereby. The upper end of said rod 13 is passed through a pair of bearing openings in plates 19 and 20, rigidly spaced apart by means of a semi-circumferential band 21, the top plate 20 being secured on said semi-circumferential band by means of bolts 22. Between said plates 19 and 20 and rotatably mounted upon said rod 13 by means of perforations 23 are a series of disks 24, each of said disks being provided with a radially extending arm 25, the lowest of said disks 26 being provided with the shortest arm and the arm of each of said disks being slightly longer than the arm of the disk below it. The free ends of said arms are provided with downwardly projecting fingers 27. The lowest arm 26 is provided with a radially extending slot 28 communicating with the opening 23 and extending exactly in the opposite direction from the opening in the next adjacent disk above. The alternate disks 24 above the disk 26 are provided with similar slots extending in the same direction as the slot 28. The disk adjacent the disk 26 is provided with a similar slot 29 which extends in the opposite direction from the slot 28. It will be seen then that when all of the arms 25 are extending in the same direction, all of the alternate slots 28 are extending in the opposite direction and the remaining slots 29

are extending in the same direction as said arms. The rod 13 is provided with a lug 30 which, when the rod is in its lowest position, is adapted to engage the notch 28 of the disk 26. When said rod is raised a distance equal to the thickness of one disk, it will engage the disk just above the disk transversely engaged until said rod engages the topmost of the disks 24.

10 Rigidly secured to the tubular support 3 opposite and spaced with said slot 9 is the back plate 31. Suitably secured to said back plate is a stub shaft 32 carrying at its forward or free end, the wheel 33 provided 15 with outwardly extending teeth 34 and forwardly projecting teeth 35. Between said wheel and said back plate are pivotally secured on said stub shaft, the pawl levers 36 and 37 carrying pawls 38 near their upper 20 ends and counter balances 39 at their lower ends.

The pawls 38 engage the outwardly extending teeth 34 throughout a portion of the movement of the levers 36 and 37 but are held from engagement with said teeth near the upper end of said movement by means 25 of an arc shaped plate 40 secured to said back plate. Near the upper ends of said levers are wires 41 adapted to connect with 30 pedals 42 and 43 secured to the lower end of said standard 1. The lever 37 carries at its upper end a forwardly curved piece having therein an eye 44 adapted to receive therein a curved rod 45 fastened to the outer end of 35 the pawl 46 pivotally secured to the outer end of a smaller lever 47 pivotally mounted upon a pin 48, rotatably mounted in a bearing 49 in said back plate and a bearing in a front plate 50 secured to the front of said 40 tubular support 3 and on which said arms 7 are pivotally mounted. The pin 48 carries a rigid wheel 51 and the pinion 52 adapted to engage the teeth 16 to move said rod 13 upwardly when the smaller lever 47 is oscillated. A box 53 may be provided to contain the mechanism thus described.

The upper end of the rod 13 is provided with a cross bar 54 carrying on the same side as is the eye 44 and the curved rod 45, a 50 short downwardly projecting wire 55 passing through a perforation 56 in the plate 20 and passing forward of any of the arms 25 pointing to the same side. The opposite end of the bar 54 is provided with a U-shaped wire 55 55 57 having its free arm 58 shorter than the long arm 59 which is secured to the end of the bar 54, said long arm passing through aligned perforations 60 in the plates 19 and 20, the free arm 58 projecting upwardly in front 60 of certain of the arms 25 when the arms are pointing on said side.

The operation of this device is as follows: The music book being opened and placed upon the board 5 has placed between the 65 leaves, a series of fingers 27 and arms 25 all

pointing on the same side as the parts 44 and 45, the fingers of the lower disks being turned first and placed behind the leaves which are to be turned, the lug 30 being received by the slot of the last disk 26. In 70 this position the wire 55 will project downwardly in front of all of the arms 25 except the lowest one. With the parts in this position, when it is desired to turn the first leaf, all that is necessary is to press upon the 75 pedal 42. This causes the lever 37 to force the pawl 38 downwardly just rotating the wheel 33 and turning the rod 13 and with it the lug 30 and the lower disk 26. This causes the slot 28 on the disk 26 to move 80 around until said slot registers with the slot 29 of the disk next above the disk 26. The arms 25 of the disks above the disk 26 are held from following the movement of the disk 26 by means of the wire 55. When the 85 next leaf is to be turned, the pedal 42 is again pressed. This pressure causes the upper end of the lever 37 to pass downwardly, the eye 44 causing, because of the engagement with the lever 47 and the rod 45, the pawl 46 to 90 rotate the pinion 52 thus raising the lug 30 into the slot 28 next above. Further movement of the lever 37 causes the pawl 38 to engage the wheel 33, thus continuing the rotation of the lug 30 and causing the second 95 plate 24 to rotate through 180 degrees. To turn the other leaves, this operation is continued, each operation bringing the non-registering slot 28 around to register with the slot of the plate just below, whereby the 100 lug 30 may rise into the notch of the next plate. Each rising movement of the rod 13 carries the wire 55 and 58 upwardly the distance of one disk, the wire 55 holding the arms 25 from following on account of friction 105 the moving arm just below it, the arm 38 each time rising the distance of the thickness of one disk in position to hold the arms on that side from following the moving disk when the leaves are turned the other way. 110 This operation is continued until the desired number of leaves have been turned. When it is desired to turn the leaves the other way, the lever 43 is pressed, thus causing the wheel 33 to rotate in the opposite direction 115 causing the lug 30 to rotate in the direction opposite the direction above described. In each case the lug 30 will carry around the non-registering slot 28 to register with the slot just above it. The action of gravity 120 will cause the lug 30 to drop into the next lower slot. This operation may be repeated until the desired number of leaves are turned.

Having thus described our invention, what we claim as new and desire to secure by U. S. 125 Letters-Patent is:—

1. In combination, a support, a rod passing through said support, a plurality of disks provided with perforations by means of which said disks are pivotally mounted upon 130

5 said rod, fingers secured to said disks, said disks being provided with radially extending slots communicating with said perforations, a lug on said rod adapted to engage any one of the slots, means to rotate said rod, means for raising said rod to place the lug in engagement with the succeeding disk, and means to prevent the rotation of certain of said disks when one of said disks is being rotated in either direction.

10 2. In combination, a support, a rod passing through said support, a plurality of disks provided with perforations by means of which said disks are pivotally mounted upon said rod, fingers secured to said disks, said disks being provided with radially extending slots communicating with said perforations, a lug on said rod adapted to engage any one of said slots, means to rotate said rod, means for raising said rod whereby any one of said slots may be selected, means to return said disks to initial position step by step and means to prevent the rotation of certain of said disks during the return of one of them.

15 3. In combination, a support, a rod passing through said support, a plurality of disks provided with perforations by means of which said disks are pivotally mounted upon said rod, fingers secured to said disks, said disks being provided with radially extending slots communicating with said perforations, a lug on said rod adapted to engage any one of said slots, rotating means to rotate said rod, and means for raising said rod whereby any one of said slots may be selected, said rotating means comprising a pinion on said rod a gear wheel having teeth adapted to engage said pinion and an oscillating pawl adapted to engage said teeth, and positive means to prevent more than one of said disks from turning at a time.

20 4. In combination, a support, a rod rotatably mounted in said support, a plurality of disks rotatably mounted upon the upper end of said rod, said disks being provided with radially extending slots, a lug on said rod adapted to engage any one of said slots, fingers projecting from said disks, the lower end of said rod being provided with an elongated pinion and a series of annular ribs just above said pinion, a crown wheel adapted to engage said elongated pinion, means for rotating said crown wheel in either direction means for engaging said ribs to raise said rod, and positive means to prevent more than one of said disks from turning at the same time.

25 5. In combination, a support, a rod rotatably mounted in said support, a plurality of disks rotatably mounted upon the upper end of said rod, said disks being provided with radially extending slots, a lug on said rod adapted to engage any one of said slots, fingers projecting from said disks, the lower end of said rod being provided with an elongated

30 pinion and a series of annular ribs just above said pinion, a crown wheel adapted to engage said elongated pinion, means for rotating said crown wheel in either direction and means for engaging said ribs to raise said rod, said means comprising a pinion engaging said ribs, a ratchet wheel rigidly secured to said pinion, and a lever and pawl adapted to engage said ratchet wheel together with a pair of pins for preventing the rotation of more than one disk in either direction.

35 6. In combination, a support, a rod rotatably mounted therein, a plurality of disks pivotally mounted around the upper end of said rod, said disks being provided with slots, a lug carried by said rod adapted to engage any one of said slots, an elongated pinion on the lower end of said rod, a series of annular ribs on said rod above said pinion, a crown wheel rotatably mounted to engage said elongated pinion, a lever carrying a pawl adapted to engage said crown wheel, a pinion to engage said ribs, a ratchet wheel rigidly secured to said pinion, a pawl to engage said ratchet wheel, connection between said pawl and said lever to operate said pawl, an additional lever carrying a pawl adapted to rotate said crown wheel in an opposite direction, pedals secured to said support and means connecting said pedals with said levers together with a pin carried by said rod to hold certain of said disks against rotation.

40 7. In combination, a support, a rod rotatably mounted therein, a plurality of disks pivotally mounted around the upper end of said rod, said disks being provided with slots, a lug carried by said rod adapted to engage any one of said slots, an elongated pinion on the lower end of said rod, a series of annular ribs on said rod above said pinion, a crown wheel rotatably mounted to engage said elongated pinion, a lever carrying a pawl adapted to engage said crown wheel, a pinion to engage said ribs, a ratchet wheel rigidly secured to said pinion, a pawl to engage said ratchet wheel, connection between said pawl and said lever to operate said pawl, an additional lever carrying a pawl adapted to rotate said crown wheel in an opposite direction, pedals secured to said support and means connecting said pedals with said levers and means to hold certain of said disks against rotation when one of said disks is rotated.
